The ornamental design for a robotic arm skin, as shown and described.

DESCRIPTION

FIG. 1 is a front view of a robotic arm skin showing our new design;

FIG. 2 is a first side view of the robotic arm skin shown in FIG. 1;

FIG. 3 is a top view of the robotic arm skin shown in FIG. 1;

FIG. 4 is a rear view of the robotic arm skin shown in FIG. 1; and,

FIG. 5 is an upper side front perspective view of the robotic arm skin showing our new design.

The broken lines in the drawings depict unclaimed environmental subject matter.
